To all whom it may concern:

Be it known that I, Benjamin Fried, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein

Figure 1 is a front view of a dress showing my new design.

The characteristic feature of my design resides in the combination on the dress disclosed of the specific sequin embroidery below the front waist yoke and along the sleeves as shown.

I claim:

The ornamental design for a dress, substantially as shown and described.

BENJAMIN FRIED.
